US0D1006554S

(12) **United States Design Patent** (10) **Patent No.:** **US D1,006,554 S**
(45) **Date of Patent:** **** Dec. 5, 2023**

(54) **KNIFE HOLDER**

(71) Applicant: **Yangjiang Nanfang Brothers Industry and Trade Co., Ltd.**, Yangjiang (CN)

(72) Inventor: **Jinzhong Lin**, Yangjiang (CN)

(73) Assignee: **Yangjiang Nanfang Brothers Industry and Trade Co., Ltd.**, Yangjiang (CN)

(**) Term: **15 Years**

(21) Appl. No.: **29/901,250**

(22) Filed: **Aug. 30, 2023**

(30) **Foreign Application Priority Data**

Aug. 25, 2023 (EM) 015032149-0001
